UNITED STATES PATENT OFFICE.

ORVILLE L. PARMENTER, OF RACINE, WISCONSIN.

DESIGN FOR A WRAPPER FOR CIGARS.

SPECIFICATION forming part of Design No. 29,491, dated October 18, 1898.

Application filed September 20, 1898. Serial No. 691,478. Term of patent 7 years.

To all whom it may concern:

Be it known that I, ORVILLE L. PARMENTER, a citizen of the United States, residing at Racine, in the county of Racine and State of Wisconsin, have invented a certain new and useful Design for Wrappers for Cigars; and I do hereby declare the following to be a full, clear, and exact description of the invention, such as will enable others skilled in the art to which it appertains to make and use the same.

This invention relates to a new and useful design for wrappers for cigars.

Referring to the accompanying drawings, Figure 1 shows the article of manufacture constituting the new design in elevation. Fig. 2 is an edge view thereof.

The article of manufacture consists of a sheet of long narrow parallel closely-arranged pockets or cells *a*, each having the lower closed end *b* and the opposite open end *c*, with a

face-piece thereof extended beyond said open end and forming a projecting lip or tape *d*, and the bellows or creased sides *e*. The said cells are all connected together on the lines *f* into the single sheet.

The essential feature of the design is the wrapper for cigars having the parallel series of cells or pockets with lips or tapes projecting from their open ends.

Having thus fully described my invention, what I claim as new, and desire to secure by Letters Patent of the United States, is—

The design for a wrapper for cigars, substantially as described and shown.

In testimony whereof I affix my signature in presence of two witnesses.

ORVILLE L. PARMENTER.
